SHOE SEWING MACHINE

Bernard T. Leveque, Wenham, Mass., assignor to
 United Shoe Machinery Corporation, Borough
 of Flemington, N. J., a corporation of New
 Jersey

Application August 25, 1937, Serial No. 160,746

41 Claims. (Cl. 112—34)

The present invention relates to shoe sewing machines, and more particularly to a sewing machine of the McKay type which comprises a straight hook needle, a rotatable shoe-supporting horn arranged to extend inside of the shoe operated upon, and a needle threading device located at the tip of the horn.

According to the usual practice in connection with the sewing of a shoe on a McKay type sewing machine, an outsole is first temporarily attached to an insole over which the margin of a lasted shoe upper has been fastened. To secure the parts permanently together, after removal from the last, a seam is sewn through the overlapping portions of the upper, insole and outsole, preferably at uniform distances from the edges of the outsole on the outside of the shoe and of the insole on the inside so that the seam will invariably pass through all three parts.

20 The proper positioning of the seam on the outer surface of the outsole is commonly effected by means of an outside gage operating either in the channel or on the edge of the sole. Inasmuch, however, as the insole is substantially smaller than the outsole, while the preferred spacing of the seam from the edges of the insole is substantially the same as from the edge of the outsole, the proper positioning of the seam on the insole can be secured only by tipping the 25 shoe slightly on the supporting horn during the sewing operation so that the line of stitches on the insole will be offset slightly within the line of stitches on the outsole.

At the shank portion, due to the shaping of the 30 parts, a somewhat greater tipping of the shoe is required than at the fore-part for the proper positioning of the stitches.

Where, due to inaccurate assembling of the 35 parts, the outsole is displaced any substantial amount from its proper position with respect to the insole, the operator must compensate for such displacement by varying the normal tipping of the shoe in one direction or the other.

40 Thus the operator, in addition to the usual manipulations of the shoes during the sewing operation, is required to impart varying tipping movements to the shoe, depending not only upon the particular portions being sewn, but also upon the accuracy of the assembling. Since the 45 stitches on the insole are hidden from view during the sewing, the operator is obliged to rely entirely upon his judgment and the "feel" of the shoe in determining the proper extent to which 50 the shoe should be tipped. Long experience and

great skill are thus required for the most successful operation of this type of machine.

It is the object of the present invention to relieve the operator to a large degree of the exercise of skill and judgment in determining the amount of tip required to be imparted to the shoe, and to control in whole or in part such tipping by the machine itself so that inexperienced and less skillful operators will position the seam without difficulty at the proper distance from the edges of both the outsole and the insole.

Further objects are to provide novel and improved work feeding and needle looping devices, particularly adapted for use in a machine of this type, which devices are more durable and reliable in operation and require the exercise of less skill and attention on the part of the operator than in previous machines.

With these and other objects in view, one feature of the present invention contemplates 20 the provision in a shoe sewing machine of the McKay type having a straight hook needle, a rotatable shoe supporting horn, and a needle threading looper at the tip of the horn, of a gage or guide projecting above, and pivotally 25 mounted on, the tip of the horn to turn about the axis of horn rotation and adapted to engage the edge of the insole and position the same with certainty at a uniform distance from the seam line. This insole gage, cooperating with the 30 outside gage which positions the seam at a uniform distance from the edge of the outsole, causes the shoe to tip more or less automatically in the proper manner to position the seam correctly on the insole. As herein illustrated, the 35 edge gage for the insole projects above the looper and the looper is actuated by a driving member engaging the under side of the looper so as to avoid interfering with the edge gage.

It is to be noted that the gage of the present 40 invention engages the insole outside of the seam line and thus is different in structure and function from guiding buttons or rolls with which it has been proposed to equip the horns of McKay sewing machines, which buttons or rolls are concentric with the needle hole in the horn and engage a channel in the insole or the edge of a pattern inside of the seam line.

Another feature of the invention relates to a 45 novel and improved rotary needle looper, more particularly intended for use in a McKay type sewing machine, but also capable of use in other machines, said looper being formed with a downwardly extending portion having gear teeth on its lower edge and an internal bearing surface 50

within which extends a hollow supporting stud carried by the horn. By this construction a looper of dimensions larger than ordinary may be employed without increasing the size of the horn at its tip, and the support for the looper may be made stronger than heretofore, so that the bearing surface of the looper may have a larger area with resulting increased durability and freedom from wear.

10 A further feature of the invention comprises means whereby the needle in a McKay type shoe sewing machine may be actuated to feed the work, thus avoiding the use of a separate feed point or awl.

15 Other features of the invention will be readily understood by one skilled in the art from the following description taken in connection with the accompanying drawings.

In the drawings Fig. 1 is a view in side elevation of a complete machine embodying the features of the present invention; Fig. 2 is an enlarged detail view in side elevation of certain of the parts connected with the looper actuating mechanism of the machine illustrated in Fig. 1;

20 Fig. 3 is a plan view, partly in section, of the same parts; Fig. 4 is a plan view, on an enlarged scale, partly broken away and in section, of the upper part of the work supporting horn; Fig. 5 is a vertical sectional view of the upper part of the horn taken along the line 5—5 of Fig. 4; Fig. 6 is a vertical sectional view, taken along the line 6—6 of Fig. 4, with the parts of the shoe being sewn shown in broken outline; and Fig. 7 is a detached, perspective view of the edge gage at the tip of the

35 horn.

Fig. 8 is a view in side elevation of the head of the machine on an enlarged scale as viewed in the same direction as Fig. 1; Fig. 9 is an enlarged sectional view, taken from the rear along the line 40 9—9 of Fig. 8, illustrating the needle bar and cast-off supporting means, certain parts having been removed or broken away; Fig. 10 is a similar view of the same parts, showing the cast-off actuating mechanism; and Fig. 11 is a detail view 45 in side elevation and partly in section of the parts shown in Figs. 9 and 10.

Fig. 12 is a plan view of the head of the machine; Fig. 13 is a detail horizontal sectional view, taken along the line 13—13 of Fig. 11; Fig. 14 50 is a similar detail view, taken along the line 14—14 of Fig. 11; Fig. 15 is a front elevation of the head and the top portion of the horn of the machine with the machine in stopped position; Fig. 16 is a detail view illustrating, in front elevation, certain portions of the needle reciprocating and feeding mechanism; Fig. 17 is a perspective view of the cast-off and the lower end of its supporting bar; Fig. 18 is a detail plan view on an enlarged scale of the needle threading 55 looper, illustrating its relation to the needle while laying the thread in the needle hook; Fig. 19 is a vertical sectional view, taken along the line 19—19 of Fig. 18; and Figs. 20 to 23 inclusive are detail views illustrating the needle, looper, and presser foot in the successive positions assumed during the formation of a stitch and feeding of the work.

The machine illustrated in the drawings is a 70 McKay type chain stitch shoe sewing machine similar in many respects to the machine described in United States Letters Patent of the present inventor No. 1,738,778, dated December 10, 1929, and has a rotatable work supporting horn, indicated at 2, a straight hook needle 4, a cast-off 5,

and a presser foot 6 arranged to cooperate with, and clamp the work against, the tip of the horn. The driving mechanism for the machine comprises an electric motor 8 mounted in the base of the machine, a vertical shaft 10, the rotation of which is controlled by means of a clutch 12 and a foot treadle 14, a horizontal main sewing shaft 16 in the head of the machine driven from the vertical shaft 10, and a lower supplementary horizontal looper shaft 18, also driven from the vertical shaft 10 and arranged to actuate through suitable connections a needle threading device or whirl 19 at the tip of the horn. The above described parts are in general constructed and arranged as in the prior machine.

15 In the prior machine of Patent No. 1,738,778, no means are provided for guiding the insole on the inside of the shoe, the operator relying upon the presser foot in the channel on the outsole to position the seam on the outsole, and tipping the 20 shoe as his experience dictated, in order to locate the seam properly on the insole.

In the machine of the drawings embodying the present invention, an edge gage has been provided which is pivotally mounted on the tip of the horn 25 and arranged to engage the outer edge of the insole and guide the same during the sewing operation. By holding the shoe against both the insole gage and the presser foot in the channel of the outsole, the proper amount of tipping 30 will automatically be imparted to the shoe to insure the correct positioning of the seam on the insole.

35 Referring to Figs. 5, 6 and 7 of the drawings herein, the edge gage consists of a vertical tongue 35 or projection 20 extending above the tip of the horn from a ring 22, to which the projection is integrally attached in proper relation to enter the crevice formed by the upstanding side of the upper and the insole. The ring 22 is pivotally 40 mounted on the bearing surfaces 23 and 24 on the outer periphery of the whirl 19, being held thereon by a bearing cap piece 25 secured to the tip of the horn by a screw 26, and engaging the inclined beveled top face of the flange 27 extending 45 laterally from the bottom of the gage ring 22.

In order to limit the rotational movement of the gage with respect to the whirl so that the gage will invariably be in proper position to engage the edge of the insole when the shoe is 50 placed over the horn preparatory to sewing, a slot 28 has been formed in the gage ring 22 through which projects the pin 30 fixed in the whirl. The position and length of the slot are such that the gage ring may turn freely with respect to both whirl and horn to a sufficient extent to permit the gage to remain in engagement with the edge of the insole throughout the sewing operation and irrespective of the rotational movement of whirl and horn in such sewing operation. 60

In the operation of the machine the whirl, as explained later in more detail, is given an oscillatory movement through approximately one-sixth of a revolution between fixed and predetermined limits, and is wholly independent of and un- 65 affected by any swinging or turning movement of the horn. Similarly, the gage ring, rotatably mounted on the whirl, is unaffected by turning movement of the horn, its extent of rotation on the whirl, however, being fixed within the limits 70 of the pin and slot connection.

In Fig. 6 are shown the relative positions of the needle and whirl, the insole and outsole gages, and in broken outline portions of the insole, upper and outsole adjacent the seam. The out- 75

sole gage in the drawing is the presser foot 6 which enters the channel in the outsole. Where the sole is not channeled, as in stitching aloft, the sole is guided from its edge, but however, the outsole may be guided, the shoe will be more or less automatically tipped merely by the operator's holding the shoe firmly against the two gages, and the seam accurately positioned inside as well as outside the shoe.

10 In order to support the whirl 19 and the gage ring 22 mounted thereon without increasing the dimensions of the horn the whirl is provided with an internal bearing surface 32 engaging the fixed tubular bearing 34 formed on the extremity of the horn, the bearing cap 25 and the edge gage ring 22 serving also to prevent vertical displacement of the whirl.

15 In the machine of the drawings, the looper or whirl is not rotated continuously in one direction, as in the prior machine above referred to, but is given oscillatory movements through approximately 60°, which has been found ample to insure threading of the needle where the hook is positioned on the back face of the needle and parallel 20 to the line of feed, instead of on the side of the needle opposite the direction of the feed as in the prior machine. The actuating mechanism for imparting these oscillations to the looper comprises bevel gear teeth 40 on the bottom face of 25 the whirl and arranged to be driven by bevel gear teeth 42 integrally formed on the end of the shaft 44 in the upper portions of the horn (see Fig. 5). This in turn is driven through gears 46 and 47 by shaft 48 in the lower part of the horn and the latter through pinion 50 and larger gear 52 by 30 vertical shaft 54 (see Fig. 1).

35 In order to protect the shoe from injury by contact with the gear teeth 40 on the looper, the tubular support 34 at the tip of the horn is provided with the flange 53 at the lower front portion thereof to underlie and cover the teeth, as shown in Fig. 5.

40 Shaft 54 is oscillated from the continuously rotating intermediate horizontal shaft 18 by 45 means of a cam and connections as shown in Figs. 2 and 3. The actuating cam fixed upon shaft 18 is indicated at 56, the cam groove, except for a small portion shown in Fig. 3, being omitted for sake of clarity of the drawings. 50 Motion is transmitted from the cam through a follower 58 to the bell crank lever 60 pivoted at 62 to the bracket 64 secured to the column of the machine. A link 66 connected at one end to the bell crank lever and at the other to an 55 arm 68 fixed upon the vertical shaft 54, imparts the desired oscillations to the shaft, the timing of the cam being such that the looper or whirl is given an oscillation of approximately 60° to lay the thread in the hook of the needle after the latter has penetrated the work and then to return to starting position as the needle rises. For the greater portion of the stitch forming cycle the looper is held stationary by an extended dwell in the cam face.

60 65 The sewing thread is led from a source of supply 70 in the base of the machine to the usual thread controlling and waxing devices and then upwardly through the horn and along the thread passage 72 and over the guiding shoulder 74 to a point immediately beneath the whirl and in its axis of rotation (see Fig. 5). The thread then passes to the eccentrically positioned thread eye 76 in the whirl or looper button 19.

70 75 In the present machine the work instead of being supported by a plate above the looper,

rests directly upon the looper or button itself, and in order to provide clearance for the thread between the button and the work so that the pressure of the latter when the presser foot is depressed will not prevent or interfere with the 5 oscillation of the looper, a thread receiving groove 78 has been provided in the upper face of the latter extending from the thread eye 76 tangentially of the needle in the direction of the feed as the looper remains stationary prior to 10 its looping action.

15 In the present machine the work is fed by the needle and to provide for its lateral feeding movement, the looper button, instead of having the usual axially disposed, circular opening only 15 slightly larger than the diameter of the needle, has a generally triangular opening as shown at 20 25. One apex of the triangle is substantially aligned with the axis of the whirl to receive the needle in its descent after penetrating the work, 20 while the two diverging sides provide ample clearance for the needle as it moves laterally to feed the work. During the greater portion of such feeding movement the whirl is stationary in the position shown in full line in Fig. 4 and in 25 broken outline in Fig. 18, so that the needle is moved along the wall 82. Before such movement is completed, the looper button is oscillated to bring the parts into full line position shown in Fig. 18 which they maintain until after the 30 needle has withdrawn from the work.

35 The needle and cast-off mechanism are illustrated in Figs. 9, 10, 11, 15 and 16. The mechanism for imparting the vertical reciprocations of the needle toward and from the work comprises 35 the block 84 (see Fig. 9) clamped upon the needle bar 86 and connected by the vertical link 88 with the arm 90 of the two-armed needle actuating lever 92 pivoted at 94 (see Fig. 16). The other arm, 96, carries a cam roll 98 positioned in a cam 40 groove (not shown) in the face of the cam disk 100, shaped to give the proper vertical reciprocations to the needle in timed relation to the movements of the other instrumentalities.

45 The lateral or feeding movements of the needle 45 are secured by imparting swinging oscillatory movements to a pivoted carrier or frame in which the needle bar is slidably mounted. The carrier as shown in Figs. 9, 10 and 11, comprises the upper and lower bearing members 102 and 104, 50 respectively, with bowed connecting member 106. The upper member 102 is pivotally mounted upon the conical bearing pins 108 clamped in the U-shaped bracket 110 secured to the head casting of the machine. Vertically disposed bores or 55 bearings are provided in the upper and lower members in which is slidably mounted the needle bar 86.

60 To prevent rotational movement of the bar in its bearings, with resulting displacement of the hook of the needle from the position required for proper looping of the thread, the block 84 is provided with a lateral extension or guide 112 received between the guiding faces 114 on the bowed connecting member 106 of the carrier (see Fig. 65 13). The lower member is provided with external bearing faces and slides back and forth in the guideway 116 in the head of the machine as the carrier is oscillated on its pivot to cause the needle to make its feeding and return move- 70 ments.

75 The carrier is oscillated through a link 118 (see Fig. 16) pivotally connected at one end to the bowed member 106 of the carrier and at the other to a slotted arm 120 on the hub 122 pivoted at 124 75

and having a second arm 126 carrying a cam roll 128 positioned in a cam groove 136 in the rear face of the cam disk 100. By adjusting the position of the link connection in the slot 132 in arm 126, the extent of feed movement of the needle, i. e. the length of the stitch, can be varied.

The cast-off 5 is mounted at the lower end of the cast-off bar 133 slidably supported at its lower end in the lower carrier member 104, and at its upper end in the block 84 secured to the needle bar. It is held from rotational movement by the roll 134 on the clamp 136 fixed to the upper end of the cast-off bar, the roll being positioned between the oppositely disposed guiding faces 138 on the carrier.

The cast-off is actuated from the needle bar by means of the block 84 fixed upon the needle bar and through which cast-off bar 133 passes. The clamp 136 fixed on the cast-off bar below the block, and the clamp 136 on the bar above the block serve as stops or abutments to be engaged by the block in its downward and upward movements, and thereby positively actuate the cast-off bar and cast-off.

In order to hold the cast-off bar raised during the initial portion of the needle stroke and until the block 84 engages the bottom clamp 136, a friction mechanism has been provided which comprises a pair of pivoted friction fingers 140 (see Fig. 10) arranged to engage yieldingly under the action of spring 142 the upper end of the cast-off bar when the latter is raised to its upward limit.

The position and spacing of the stops or abutments on the cast-off bar are such that the cast-off is actuated in proper timed relation to the needle with the usual dwells at the ends of each of the downward and upward strokes of the needle.

In the present machine the needle is required to perform the entire work-puncturing operation with no preliminary or partial puncturing by a feed point as in the above mentioned prior machine. Furthermore, the work is fed solely by the needle instead of by such feed point. To guide and support the needle during these puncturing and feeding movements and prevent its buckling or bending or springing out of proper cooperative relation to the cast-off, the latter has been formed with supplementary needle supporting means consisting of an encircling band or sleeve 144 (see Fig. 17) which surrounds the shank of the needle with a sliding fit.

The mechanism for actuating the presser foot comprises a presser foot bar 150, urged downwardly by the spring 158 surrounding the bar (see Fig. 15) and also by a spring 160 surrounding shaft 162 and secured at one end to the collar 163 fast on the shaft, and at the other end to the collar 164 adjustably mounted on the machine frame (see Fig. 8). An arm 170 fast on shaft 162 is connected by link 174 to the presser foot supporting lever 176 in which the shank of the presser foot 6 is secured (see Fig. 15). The bar is raised against the tension springs 158 and 160 by mechanism, best shown in Fig. 16, which comprises the block 177 fast on the presser bar and carrying the pivotally mounted block 178 with a V-shaped groove in its lower face, cooperating with V-shaped edge 180 of lifting lever 182. The latter lever is pivotally supported at 183 on the end of arm 184 on rock shaft 186 which is actuated through arm 18, link 190, and cam lever 192 with cam roll 193 engaged by cam 194. Thus with each cycle of operation of the

machine the lifting lever 182 is raised and with it the presser foot bar and the presser foot.

In order to impart a uniform lift of the presser foot above the work, regardless of variations in the thickness thereof, the presser foot supporting lever 176 is laterally extended and provided at its end with the roll 200 engaging the included ledge 206 at the lower end of pivoted lever 202, connected at its upper end by link 204 to lifting lever 182. A coiled spring 208 (see Fig. 15) tends to turn lever 202 clockwise to bring the ledge 206 into engagement with roll 200 and to swing lifting lever 182 counter-clockwise to engage block 178, opposite movements of these parts being caused by downward movement of the roll 200 in engagement with ledge 206. A stop screw 212 limits the movement of lever 202 when the machine is stopped with the presser foot raised as shown in Fig. 15.

The presser foot and its actuating mechanism above described are in general the same in construction as in the machine of the prior patent. In operation the presser foot is raised and lowered in timed relation to the movements of the looper or whirl and of the needle so that during the looping and feeding movements of these devices the presser foot will be raised and the work freed from pressure. Thus, Fig. 20 shows the needle in the work and the thread-looping movement of the whirl just completed, the presser foot being raised during such movement. In Fig. 21 the needle has finished its work feeding movement toward the left, the presser foot being still raised. In Fig. 22 the needle is drawing a loop of thread through the work and the previously formed loop, the presser foot now being depressed and clamping the work firmly against the horn and whirl. In Fig. 23 the needle is fully retracted and returned to its original position for penetrating the work, the presser foot still being held depressed to clamp the work.

While the drawings show in more or less detail other mechanisms and devices which form a part of the machine, these need not be here described since they form no part of the invention disclosed and claimed herein. They are the same in construction and operate in the same manner as the corresponding mechanisms and devices in said prior patent, to which reference may be made for a full and complete description.

The operation of the machine as a whole is in general the same as the machine of the prior patent, except in connection with those devices and mechanisms which are directly connected with the invention and made the subject of the present invention. As to these parts the operation is as follows:

Assuming the machine to be at rest, the operator will position a shoe upon the horn with the insole gage in contact with the edge of the insole within the shoe which is then tipped, as shown in Fig. 6 to bring the presser foot into the channel in the outsole. With the presser foot holding the work clamped tightly against the whirl and horn, the sewing mechanism is set in operation and the needle is forced downwardly through the work and into the opening in the whirl. The parts are then in the position shown in Fig. 23, with the needle in broken line. (See also Figs. 4 and 6.) The presser foot is then raised and the needle given a slight upward movement to relieve the whirl which is given its looping motion, to lay the thread in the 75

barb of the needle, bringing the parts to the position shown in Fig. 20. With the presser foot still raised, the needle is given its feeding stroke, moving to the position shown in Figs. 18 and 21, and upon completion thereof the presser foot again clamps the work and the needle lifts to draw the loop of thread through the last formed loop, as shown in Fig. 22.

As the needle approaches the top of the upward movement, it is given its backward idle stroke to its initial position and ready for the next downward stroke, the parts being then as shown in full lines in Fig. 23, and during the latter portion of said movement the looper is given its return rotation.

As the sewing proceeds around the shoe, the presser foot and the edge gage are maintained in engagement with the channel in the outsole and the edge of the insole, respectively, thereby effecting or tending to effect a tipping of the shoe in the hands of the operator so that the needle will always emerge from the insole within the shoe at the predetermined, uniform distance from the edge of the insole, irrespective of irregularities in the overlap of the outsole due to imperfect positioning of the outsole and the insole, or for any other reason.

As the shoe and horn turn, the insole gage will adjust itself, as may be required, to maintain engagement with the edge of the insole, the range of rotational movement of the gage being for this purpose sufficient.

By using the needle to feed the work, the feed point is eliminated from the machine, not only reducing the number of operating instrumentalities, but making it possible to locate the presser foot much nearer the needle so that it will be more effective in clamping the work upon the horn and a tighter seam will be secured than with the prior machine of the patent.

By the novel construction and arrangement of the whirl and horn, the former may be of ample size and the contacting parts of sufficient dimension to avoid excessive wear. The positioning of the hook of the needle on the back side thereof also makes it possible to lay a thread in the hook with a minimum of rotational movement of the whirl and its driving mechanism, which is a feature of advantage.

While the present invention has been shown and described as embodied in the specific construction shown and illustrated in the drawings, it is to be understood that the form and arrangement of the various parts and mechanisms may be modified and changed without departing from the present invention as defined in the appended claims.

Having thus described the invention, what is claimed is:

60. 1. A shoe sewing machine of the McKay type having, in combination, stitch forming and work feeding devices including a hook needle, a rotatable work supporting horn, and a gage pivotally mounted on the horn constructed and arranged to engage a shoe part on the inside of the shoe outside of the seam line and determine the location of the seam with relation to the edge of the insole, the gage turning relatively to the horn to maintain proper cooperative relation with the shoe part during the sewing operation.

2. A shoe sewing machine of the McKay type having, in combination, stitch forming and work feeding devices including a hook needle, a rotatable work supporting horn, and an insole gage pivotally mounted on the horn constructed and

arranged to engage the edge of the insole on the inside of the shoe outside of the seam line, the gage turning relatively to the horn to maintain proper cooperative relation to the edge of the insole as the shoe is turned on the horn during 5 the sewing operation.

3. A shoe sewing machine of the McKay type having, in combination, stitch forming and work feeding devices including a hook needle, a rotatable work supporting horn, a looper mounted to turn on the horn, and a gage pivotally mounted on the horn coaxially with the looper constructed and arranged to engage the edge of the insole on the inside of the shoe outside of the seam line, the gage turning relatively to the horn and to 10 the looper to maintain proper cooperative relation to the edge of the insole during the sewing operation.

4. A shoe sewing machine of the McKay type having, in combination, stitch forming and work feeding devices including a straight hook needle, a rotatable work supporting horn, a looper mounted to turn on the horn, and a gage rotatably mounted on the looper to engage the edge of the insole on the inside of the shoe, the gage 20 turning with respect to the looper and to the horn to maintain proper cooperative relation to the edge of the insole during the sewing operation.

5. A shoe sewing machine of the McKay type having, in combination, stitch forming and work feeding devices including a straight hook needle, a rotatable work supporting horn, a looper mounted to turn on the tip of the horn and having an axial, needle-receiving opening, and an insole gage comprising an annular member pivotally mounted on the looper and having a projecting lip to engage the edge of the insole on the inside of the shoe, the gage turning on the looper to maintain proper cooperative relation 25 to the edge of the insole during the sewing operation.

6. A shoe sewing machine of the McKay type having, in combination, stitch forming and work feeding devices including a hook needle, a rotatable work supporting horn, and an annular member pivotally mounted on the horn and having a lip projecting upwardly therefrom to engage the edge of the insole of the shoe outside of the seam line to locate the seam on the inside of the shoe. 50

7. A shoe sewing machine of the McKay type having, in combination, stitch forming and work feeding devices including a hook needle, a rotatable work supporting horn, a looper mounted to turn on the horn, a gage pivotally mounted on the horn coaxially with the looper constructed and arranged to engage the edge of the insole on the inside of the shoe outside of the seam line, the gage turning relatively to the horn and to the looper to maintain proper cooperative relation to the edge of the insole during the sewing operation, and means for limiting the rotational movement of the gage. 55

8. A shoe sewing machine of the McKay type having, in combination, stitch forming and work feeding devices including a straight hook needle, a rotatable work supporting horn, a looper mounted to turn on the horn, a gage rotatably mounted on the looper to engage the edge of the insole on the inside of the shoe, the gage turning 65 with respect to the looper and to the horn to maintain proper cooperative relation to the edge of the insole during the sewing operation, and a pin and slot connection between the gage and the looper for limiting the range of rotational 70 movement of the gage.

75

- movement of the gage with respect to the looper.
9. An insole gage for shoe sewing machines comprising an annular member provided with a bearing surface to support the gage rotatably and having a lip projecting from the member and adapted to engage the edge of the shoe insole outside of the seam line.
10. An insole gage comprising an annular member having an upwardly extending guiding lip, a central bore to provide an internal bearing surface to support the gage rotatably, and a laterally extending flange having top and bottom bearing faces.
11. An insole gage for shoe sewing machines comprising an annular member having bearing surfaces for rotatably supporting the same, the member being provided with a guiding lip extending therefrom adapted to engage the edge of an insole outside of the seam line, and with means for limiting the extent of rotation of the member.
12. A shoe sewing machine of the McKay type having, in combination, stitch forming and work feeding devices including a hook needle, a rotatable work supporting horn having an external bearing surface at the tip thereof, a looper having an internal bearing surface adapted to turn upon the bearing surface on the horn, the looper being provided with an axial opening to receive the needle.
13. A shoe sewing machine of the McKay type having, in combination, stitch forming and work feeding devices including a straight hook needle, a rotatable work supporting horn having a tubular support at its tip with an outer bearing surface thereon, a looper mounted to turn upon said tubular support and having a needle receiving opening axially disposed with respect to the looper and to the support and an eccentric thread receiving opening aligned with the bore of the tubular support.
14. A shoe sewing machine of the McKay type having, in combination, stitch forming and work feeding devices including a straight hook needle, a rotatable work supporting horn having a tubular support at its tip with an outer bearing surface thereon, a looper mounted to turn upon said tubular support, and driving means for the looper comprising a member engaging the under face of the looper.
15. A shoe sewing machine of the McKay type having, in combination, stitch forming and work feeding devices including a straight hook needle, a rotatable work supporting horn having a tubular support at its tip with an outer bearing surface thereon, a looper mounted to turn upon said tubular support, and driving means for the looper comprising gear teeth on the under face of the looper, and a shaft mounted to turn in the horn having gear teeth engaging the teeth on the looper.
16. A shoe sewing machine of the McKay type having, in combination, stitch forming and work feeding devices including a straight hook needle, a rotatable shoe supporting horn, a rotary looper mounted at the tip of the horn having a surface to support the work adjacent the thrust of the needle, said surface being provided with a depression to receive the thread between the work and the looper.
17. A shoe sewing machine of the McKay type having, in combination, stitch forming and work feeding devices including a straight hook needle, a rotatable shoe supporting horn, a rotary looper mounted at the tip of the horn, and means for actuating the looper first in one direction and then in the other through an angle not greater than sixty degrees to lay the thread in the hook of the needle.
18. A shoe sewing machine of the McKay type having, in combination, stitch forming and work feeding devices including a straight hook needle having a hook facing at substantially right angles to the line of feed, a shoe supporting horn, a rotary looper at the tip of the horn, and means for actuating the looper to lay the thread in the hook of the needle.
19. A shoe sewing machine of the McKay type having, in combination, stitch forming and work feeding devices including a straight hook needle, a rotatable work supporting horn having a tubular support at its tip with an outer bearing surface thereon, a looper mounted to turn upon said tubular support and driving means for the looper comprising a member engaging the under side of the looper, the horn being extended to cover the teeth on the looper to prevent contact of the teeth with the work.
20. A shoe sewing machine of the McKay type having, in combination, stitch forming and work feeding devices including a straight hook needle, a rotatable work supporting horn having its tip extending laterally to form a tubular support cut away at its lower portion adjacent the horn to form a cut away, shaft-receiving opening, a looper mounted to turn upon the support, and a shaft mounted in the horn adjacent the support and extending into the opening for actuating the looper.
21. A shoe sewing machine of the McKay type having, in combination, stitch forming and work feeding devices including a straight hook needle, a rotatable work supporting horn having a tubular support at its tip with an outer bearing comprising vertical and horizontal bearing surfaces, a looper having on its inner and bottom portions vertical and horizontal bearing surfaces engaging said surfaces on the support and being provided at its outer and top portions with vertical and horizontal bearing faces, an annular gage member having inner and bottom bearing surfaces engaging the bearing surfaces on the outer and top portions of the looper and provided at its outer and top portions with vertical and outwardly beveled bearing surfaces, and a cap piece secured to the horn and engaging said last mentioned bearing surfaces on the gage for retaining the gage and the looper in operative position on the support on the horn.
22. A shoe sewing machine of the McKay type having, in combination, stitch forming and work feeding devices including a straight hook needle, a rotatable work supporting horn having a tubular support at its tip with an outer bearing surface thereon, a looper mounted to turn upon said tubular support, a gage mounted to turn on the looper, and a cap piece secured to the horn for retaining the gage and the looper in operative position.
23. A shoe sewing machine of the McKay type having, in combination, stitch forming and work feeding devices including a straight hook needle, a rotatable work supporting horn, and a looper mounted to turn on the tip of the horn and having an eccentric thread eye, the horn being provided with an open thread passage on its lower face to guide the thread to said eye.
24. A shoe sewing machine of the McKay type having, in combination, stitch forming and work feeding devices comprising a hook needle, a rotatable work supporting horn, a looper mounted to turn on the horn and to lay the thread in

the hook of the needle, and means for moving the needle laterally when in the work to feed the same.

25. A shoe sewing machine of the McKay type having, in combination, stitch forming and work feeding devices comprising a hook needle, a rotatable work supporting horn, a looper having an axially disposed needle receiving opening and mounted to turn on the horn and to lay the thread in the hook of the needle, and means for moving the needle laterally when in the work to feed the same.

26. A shoe sewing machine of the McKay type having, in combination, stitch forming and work feeding devices comprising a hook needle, a rotatable work supporting horn, a looper having an axially disposed needle receiving opening shaped to permit rotational movement of the looper and lateral movement of the needle when the latter is in the opening, and means for rotating the looper and for moving the needle laterally to feed the work.

27. A shoe sewing machine of the McKay type having, in combination, stitch forming and work feeding devices comprising a hook needle, a rotatable work supporting horn, a looper having a triangular needle receiving opening and mounted to turn on the horn to lay the thread in the hook of the needle, and means for moving the needle laterally when in the work to feed the same.

28. A shoe sewing machine of the McKay type having, in combination, stitch forming and work feeding devices comprising a hook needle, a rotatable work supporting horn, a looper having an elongated needle receiving opening and mounted to turn on the horn to lay the thread in the hook of the needle, and means for moving the needle laterally when in the work to feed the same.

29. A shoe sewing machine of the McKay type having, in combination, stitch forming and work feeding devices including a straight hook needle, a rotatable shoe supporting horn, and means for actuating the needle including mechanism for moving the needle laterally when in the work to feed the same.

30. A shoe sewing machine of the McKay type having, in combination, stitch forming and work feeding devices including a straight hook needle, a rotatable shoe supporting horn, a needle bar, a carrier pivoted at its upper end and in which the needle bar reciprocates toward and from the work, and means for swinging the carrier while the needle engages the work to feed the same.

31. A shoe sewing machine of the McKay type having, in combination, stitch forming and work feeding devices including a straight hook needle, a rotatable shoe supporting horn, means for actuating the needle including mechanism for moving the needle laterally when in the work to feed the same, a presser-foot adjacent the needle, and means for actuating the presser-foot to clamp the work adjacent the horn and close to the needle when the latter is making its loop drawing and work penetrating strokes.

32. A McKay type shoe sewing machine having, in combination, stitch forming devices including a straight hook needle, a needle looper, a shoe supporting horn in which the looper is mounted, a presser-foot operating at the same side of the work as the needle to clamp and release the work on the horn, a reciprocating needle bar, a carrier in which the needle bar recip-

rocates, means for actuating the carrier while the needle engages the work to feed the same, and mechanism for reciprocating the needle bar to cause the needle to enter the horn while the presser-foot clamps the work against the horn and to withdraw partly from the horn before feeding the work.

33. A McKay type shoe sewing machine having, in combination, stitch forming devices including a straight hook needle, a needle looper having a surface to provide support for the work against the thrust of the needle, a presser-foot operating at the same side of the work as the needle to clamp and release the work, and mechanism for actuating the needle first in one direction while the work is clamped to penetrate the work, and then in the reverse direction while the work is released to relieve the looper from the pressure of the work before the looper acts to lay the thread in the needle hook.

34. A McKay type shoe sewing machine having, in combination, stitch forming devices including a straight hook needle, a rotary needle looper having a needle receiving opening and a surface surrounding the needle opening to provide support for the work against the thrust of the needle, a presser-foot operating at the same side of the work as the needle to clamp and release the work, and mechanisms for actuating the needle first in one direction to penetrate the work and then in a reverse direction while the work is released to relieve the looper from the pressure of the work, and for rotating the looper to lay the thread in the needle hook after the needle has been actuated to relieve the looper.

35. A McKay type shoe sewing machine having, in combination, stitch forming devices including a straight hook needle, a rotary needle looper having a needle receiving opening and a surface surrounding the needle opening to provide support for the work against the thrust of the needle, a presser-foot operating at the same side of the work as the needle to clamp and release the work, and mechanism for actuating the needle first in one direction to penetrate the work and then in a reverse direction while the work is released to relieve the looper from the pressure of the work, and for rotating the looper while the looper is relieved in one direction to lay the thread in the hook of the needle and then in reverse direction to locate the thread at the hook side of the needle before the next thrust thereof.

36. A shoe sewing machine of the McKay type having, in combination, stitch forming and work feeding devices including a straight hook needle, a rotatable shoe supporting horn, a cast off having a guide portion completely surrounding the needle to reinforce it close to the surface of the work while the needle is feeding the work, and means for actuating the needle including mechanism for moving the needle laterally when in the work to feed the same.

37. A shoe sewing machine of the McKay type having, in combination, stitch forming and work feeding devices including a hook needle, a rotatable work supporting horn, and a gage pivotally mounted on the horn constructed and arranged to engage a shoe part on the inside of the shoe outside of the seam line and determine the location of the seam with relation to the edge of the insole, the gage being held from rotation within limits and unaffected by the rotation of the horn.

38. A shoe sewing machine of the McKay type

75 75

- 5 having, in combination, stitch forming and work feeding devices including a hook needle, a rotatable work supporting horn, a looper and an edge guide on the horn, and connections between the looper and guide to control the position of the guide while permitting free rotation of the horn.
- 10 39. A shoe sewing machine of the McKay type having, in combination, stitch forming and work feeding devices including a hook needle, a rotatable work supporting horn, a looper, and a gage mounted on the looper to turn within fixed limits and unaffected by movements of the horn.
- 15 40. A shoe sewing machine of the McKay type having, in combination, stitch forming and work feeding devices including a hook needle, a rotatable work supporting horn, a looper mounted to
- 5 turn on the horn, means for rotating the looper within fixed limits and independently of movements of the horn, and a gage mounted to turn on the looper within limits and unaffected by movement of the horn.
- 10 41. A shoe sewing machine of the McKay type having, in combination, stitch forming and work feeding devices including a hook needle, a rotatable work supporting horn, a looper mounted to turn upon the horn the looper being provided with a needle receiving slot, means for moving the needle laterally along the slot when in the work to feed the latter, and means for holding the looper with the slot in the line of feed during the lateral feeding movement of the needle 15 and unaffected by the movement of the horn.

BERNARD T. LEVEQUE.
